UNITED STATES PATENT OFFICE.

FREDERICK J. MELLEN AND BURTON A. EDWARDS, OF BELOIT, WISCONSIN.

RECOIL-COMPENSATOR.

No. 896,136.

Specification of Letters Patent. Patented Aug. 18, 1908.

Application filed November 14, 1907. Serial No. 402,217.

To all whom it may concern:

Be it known that we, FREDERICK J. MELLEN and BURTON A. EDWARDS, citizens of the United States, residing at Beloit, in the county of Rock and State of Wisconsin, have invented certain new and useful Improvements in Recoil-Compensators, of which the following is a specification.

This invention comprehends certain new and useful improvements in that class of devices that are designed to be interposed between the body and axle or springs of a vehicle in order to compensate for the rebounding action of the springs after they have been compressed, owing to the vehicle passing over uneven places in the road, and our invention has for its object a simple, durable and efficient construction of recoil compensator of this character which will be composed of comparatively few parts that may be cheaply manufactured and easily assembled and that will not be liable to get out of order.

With these and other objects in view as will more fully appear as the description proceeds, the invention consists in certain constructions, arrangements and combinations of the parts that we will hereinafter describe and then point out the novel features in the appended claims.

For a full understanding of the invention reference is to be had to the following description and accompanying drawings, in which:

Figure 1 is a side elevation of our improved shock compensator showing it in applied position; Fig. 2 is a longitudinal sectional view thereof; Fig. 3 is a transverse sectional view; and, Fig. 4 is a detail perspective view of the piston.

Corresponding and like parts are referred to in the following description and indicated in all the views of the drawings by the same reference characters.

Our improved recoil compensator comprises a cylinder 1 embodying front and rear heads 2 and 3 secured to the body portion by screw-bolts or any other desired means, said body portion being formed with base extensions 4 by which the cylinder may be secured to the springs or axle of the vehicle as by the clips 5. The interior of the cylinder 1 constitutes a chamber 6 for oil or some similar fluid medium, and the partition 7 is secured by screws or the like in said chamber, said partition being in the form of a block, as shown, preferably fitting a recess in the wall

of the chamber 6, the sides of said block tapering towards the center of the chamber.

A piston 8, which, in the present instance, is in the form of a segmental block, as best seen in Fig. 4, is mounted to oscillate in the chamber 6 about the center of the chamber, as an axis, and said piston is formed with a laterally projecting shaft extremity 9 extending out of the cylinder through a stuffing box 10. An arm 11 is secured at one end to the protruding end of the shaft 9 of the piston 8, the other end of said arm being connected by a link 12 or any other suitable means to some portion of the vehicle body. 70

The piston 8 is formed with a passage 13 extending therethrough from one side to the other so as to establish communication between the opposite sides of the chamber 6 as regards the said piston, it being understood that the piston is of a width to fit frictionally between the heads 2 and 3, and of a length and contour to snugly fit the wall of the chamber 6. A check valve 14 is mounted within one end of the passage 13 and is designed to close said passage, said check valve being held yieldingly on its seat by means of a helical compression spring 15 secured to the check valve and to a transverse pin 16 extending across the passage 13 and secured in the piston, as best seen in Fig. 3. 80

In addition to the passage 13, the piston 8 is formed with a port 17 which intercepts the bore 9^a of the hollow shaft extension 9 of the piston, and a screw plug 18 is mounted in said bore 9^a and is designed to vary the area of the port 17, transversely considered, so as to regulate the size of the passage formed thereby, in an evident manner. 90

In the practical operation of our improved recoil compensator for the springs of automobiles and other vehicles, it will be understood that the compression of the springs for supporting the body, that is, the tension under which the springs are placed upon the downward movement of the body, is in no sense retarded, because the downward movement of the arm 11 will turn the piston 8 in such a direction that the oil or other medium in the chamber 6 may unseat the valve 14 100 and flow freely through the passage 13 from one side of the piston to the other. Upon the recoil movement, however, the check valve 14 will effectively close the passage 13, and, owing to the partition 7, the oil or other fluid medium will be forced through the relatively small port 17, so that the flow of the fluid me- 105 110

dium will be effectively retarded until equilibrium is restored. Hence, all of the unpleasant shock incident to the sudden recoil of the springs will be absorbed or avoided, 5 while at the same time the arrangement of parts provides that the springs may yield to their fullest extent upon the downward movement of the vehicle body when traveling over an uneven road.

10 Having thus described the invention, what is claimed as new is:

1. A recoil compensator of the character described, comprising a cylinder forming a chamber for a fluid medium, a solid partition 15 secured in said chamber, a piston mounted to oscillate in said chamber, and formed with a passage extending therethrough, and a relatively small port also extending therethrough, a spring pressed check valve 20 connected to said piston and adapted to close said passage, the piston being formed with a laterally projecting shaft extension extending out of the cylinder, said extension being formed with a bore intercepting said 25 port, an operating arm secured to said extension, and a plug mounted in said bore and adapted to vary the size of the port, as and for the purpose set forth

2. A recoil compensator comprising a cylinder, providing a chamber for a fluid medium, a partition secured in said chamber, a piston mounted to slide in said chamber and formed with a passage extending therethrough, a check valve adapted to close against one end of said passage, a pin secured in the 35 piston and extending transversely of said passage, a compression spring connected to said pin and valve and adapted to yieldingly hold the valve against the end of the piston, said piston being formed with a laterally projecting 40 shaft extension protruding from the cylinder, an operating arm secured to said shaft extension, said shaft extension being formed with a bore extending into the piston, the piston being formed with a port extending entirely 45 therethrough and intercepting the inner end of the bore, and a plug working in the bore and adapted to vary the size of the port.

In testimony whereof we affix our signatures in presence of two witnesses.
